DEICING SYSTEM FOR PROPELLERS

Charles W. Chilson, Caldwell, and Ward E. Brigham, Jr., Packanack Lake, N. J., assignors to Curtiss-Wright Corporation, a corporation of Delaware

Application August 16, 1946, Serial No. 691,125

2 Claims. (Cl. 244—134)

1

This invention relates to aeronautical propellers and is concerned particularly with manifolding and ducting systems on controllable pitch propellers by which hot gas may be fed to the propeller during operation for preventing the formation of ice on the blades or for removing ice which may form on the blades.

It is known in the art that ice formation on propellers may be prevented by heating the propeller blades and various means have been proposed and used for this purpose, including the application of hot gas to the interior portions of hollow blades. Where hot gas is fed to the blades, it is ordinarily necessary to design special propellers so that the hot gas ducting may be incorporated in the basic propeller design, but we have found that a hot gas de-icing system can be applied to existing propellers.

It is an object of this invention to provide a hot gas manifolding system for a propeller by which a hot gaseous medium may be fed from a stationary part of the aircraft power plant to the interior cavities of hollow blades. A further object of the invention is to provide ducting and manifolding elements which can be applied to existing types of propellers without extensive modification. Another object of the invention is to provide ducting and manifolding devices which may be applied to an existing type of propeller without major disassembly of the propeller. Still another object is to provide ducting and manifolding devices for a propeller which will be effective to confine the hot gaseous medium to its intended path without undue leakage, a related object being to provide sealing means in the ducting and manifolding system which will permit limited relative motion between the propeller blades and their hub and between the propeller hub and the power plant to which it is attached while still retaining adequate sealing of the hot gaseous medium. In this connection, aircraft propellers operate under varying stress conditions and it is inevitable that the propeller blades will weave in their hub during operation and that the propeller will weave with respect to the power plant, even though these parts are secured in more or less fixed relation to one another. The stresses incident to flight operation cause this weaving. Unless a hot gas manifolding system takes into account the problems of relative yield of the parts in operation, such a system is likely to be deficient in that undue leakage and wastage of the de-icing medium will be permitted.

Still another object of the invention is to pro-

2

vide a ducting and manifolding system by which hot de-icing fluid may be transmitted both to the blades of a controllable pitch propeller and to the interior portions of cuffs which are secured to the propeller blades.

Further objects of the invention along with a better appreciation of the scope thereof, will become apparent in reading the annexed detailed description in connection with the drawings in which similar reference characters designate similar parts, and in which Fig. 1 is a longitudinal section through a propeller, hub and hub mounting incorporating features of the invention;

15 Fig. 2 is an enlarged fragmentary elevation, partly in section, showing details of the manifold structure;

Fig. 3 is a section on the line 3—3 of Fig. 2;

10 Figs. 4, 5 and 6 are perspective elevations of parts of the blade manifold;

Fig. 7 is an enlarged fragmentary elevation, partly in section, of an alternative embodiment of the invention; and

15 Fig. 8 is a section on the line 8—8 of Fig. 7.

20 First referring to Figs. 1 through 6, an engine or power plant shaft 12 extends leftwardly from a stationary power plant housing 13, and a propeller hub 14 is secured in conventional fashion to the shaft 12. The propeller shown is of the electrically operated type wherein a series of slip rings 17 form part of the rear of the hub 14, said slip rings being engaged by brushes, not shown, by which electrical energy is fed to the propeller pitch change power unit. The power unit is normally mounted on the front face of the hub 14 but this assembly is not shown as it forms no part of the present invention. The particular details of the propeller are not important, as the invention is applicable to any form of propeller. The hub 14 is provided with a plurality of integral blade sockets 15 within which blades 16 are secured. Only one socket and blade is shown as being typical of all sockets and blades. Blade securing is afforded by an internal nut 18 (Fig. 2) which, after being screwed into the socket 15, is secured from rotation by a keeper 20 screwed as at 21 to the nut 18, said keeper having a tab 22 engaging one of several vernier slots in the upper face of the blade socket.

25 The blade 16 is hollow and, as shown, is provided with one or more ports 24 in its shank portion so that a hot gaseous medium may flow into the hollow of the blade for prevention of ice. Ordinarily, the blade 16 is provided with a vent 30 opening near its tip.

We provide a stationary annular member 26 secured as at 27 to the power plant nose 13. The member 26 extends forwardly to embrace the slip rings 17 and then extends outwardly to form an annular disc parallel to the propeller plane of rotation and rearwardly of the propeller hub 14. This member, circular at its periphery, carries a peripheral groove 28 to which is fitted a seal ring 30. The ring engages a cylindrical portion 32 forming the periphery of a disc 34 secured at 36 to a rearward portion of the propeller hub 14, said disc 34 being rotatable with the propeller. The member 26 carries a manifold 38 having an entrance flange 40 to which a duct leading from a source of hot gas is secured. Hot gas flows through the manifold 38 and then through segmental openings 42 formed in the member 26. The disc 34 is provided with openings 44 lying opposite the openings 42 so that the hot gas in the manifold may flow with little loss of pressure into the rotating propeller system. Loss of hot gas between the member 26 and the disc 34 is minimized by the seal ring 30 which permits relative rotation between the member and disc and which further allows a limited amount of axial and radial freedom so that the propeller hub may weave slightly with respect to the power plant nose without interfering with the effectiveness of the hot gas seal.

To the end of each blade socket nut 18 a ring 48 (Fig. 6) is secured by the screws 21, said ring having tabs 50 through which the screws pass and being split as shown for assembly, or not split, as desired. The exterior of the ring 48 is grooved as at 52 and a split ring 54 similar to a piston ring is inserted in this groove. Around the ring 48, a band 56 (Fig. 5) is wrapped, this band being split as at 58 and being provided with tabs 60 which may be drawn together by bolts 62 to close the band and make it gas-tight. The band, for assembly, is spread and slipped over the propeller blade shank and is then clamped by the bolts 62 around the ring 54 and around an upper ring 64 forming a top closure for the band element. The lower ends of the band 56, adjacent the split 58, are provided with projections 66 which engage beneath the ring 54 to hold the band assembly from outward displacement under the influence of centrifugal force. That portion of the band opposite the split 58 is provided with an opening 68 and a fitting 70 which lies against the inner face of the disc 34 and is secured thereto by screws 72. The rear of the band 56 is secured from outward displacement due to centrifugal force by its attachment to the disc 34 while the front of the band is secured from outward displacement by the projections 66 as described. The band is sealed with respect to the ring 48 (which may be split or solid) by the split ring 54 whose periphery engages the inner face of the band. The portion of the band adjacent the split 58 is provided with a tab 74 which overlaps the opposite band portion to provide a connection seal at the band split when the band is secured by the bolts 62.

The outer rim of the band 56 is provided with a plurality of bent over tabs 76 which, during assembly, are inserted into a groove 78 formed in the outer edge of the two halves of the split ring 64. The split ring 64 is also provided with an interior groove 80 to receive a seal ring 82. The ring 82 if desired, may be made of carbonaceous material for heat resistance and effective sealing and if so made, would comprise two

halves. To secure these halves in sealing relationship to the shank of the blade 16, which they embrace, an interiorly tapered solid ring 84 is placed within the groove 80 after which the ring elements 82 are inserted, the latter having tapered peripheries coacting with the tapers of the ring 84, the whole being assembled around the blade shank with the closure 64 after which the band 56 is assembled with the tabs 76 in the groove 78. With propeller rotation, the ring 84 is urged outwardly by centrifugal force, wedging, by virtue of the tapers, the ring halves 82 into firm sealing engagement with the blade shanks.

With the assembly of the band 56, the ring 48, 15 the closure ring 64, the related seals, and the disc 34, it will be seen that a chamber or manifold 86, gas-tight in character, is formed around the propeller blade shank so that hot gas admitted from the manifold 38 through the openings 42, 44 and 70 will pass around the blade shank and into the blade hollow through the blade shank opening 24. Most of this assembly 20 may be applied to the blade shank without removing the blade 16 from the socket 15 and no 25 major modification of any of the normal propeller components is required. The manifold assembly around the blade shank can be readily removed for servicing of either the gas ducting system or of the propeller itself.

The disc 34 may, if desired, form a rearward 30 spoke element to support a propeller spinner 90 which is secured at its rearward end by bolts 92 to a suitable flange 94 formed integral with the disc 34. The spinner 90 extends around and 35 forwardly of the propeller hub, openings 96 being formed in the spinner for the propeller blades, and a part of the spinner forward of the propeller may be given further support by a spoke or diaphragm member 98 secured at its 40 outer periphery to the spinner and at its inner periphery to a spinner support 100 secured as at 102 to the propeller hub 14.

In the operation of the propeller with the gas manifold system installed, the blade 16 may weave within its socket 15 whereupon the seal ring 82 will move freely in a radial direction within its groove 80 in the member 64. The blade is free for pitch changing rotation in the socket by rotation of the ring 82 in its groove 45 or of the blade relative to the ring. Sealing effectiveness is maintained during propeller operation by the combined action of the ring 84 on the seal ring 82 and by the tendency for centrifugal force to force the outer surface of the ring 50 82 against the surface of the groove 80. The closure 64 is constrained against displacement by centrifugal force by engagement of the tabs 76 with the member 64. The band 56 is constrained against displacement due to centrifugal force by the securement to the disc 34 and by the engagement of the tabs 66 with the ring 55 54 which in turn is constrained against displacement by the securement of the ring 48 to the propeller hub assembly.

Reference may now be made to Figs. 7 and 8 60 wherein an alternative arrangement of the invention is shown. The annular member 26 with its hot gas manifold 38 and its peripheral seal ring 30 is substantially the same as in the previously 65 described embodiment. The disc 34 is also similar to that already described except for certain modifications concerned with its attachment to the blade embracing manifold, which comprises a chamber forming means.

The blade embracing manifold or chamber

forming means comprises a band 106 embracing the shank of the blade 16, the lower edge of the band being secured by screws 108 to a sleeve 110 which is fitted around the outer end of the blade socket 15. The sleeve 110 is provided with an outer flange 112 resting against the outer face of the blade socket to limit its inward movement. The bottom end of the sleeve 110 is provided with a plurality of slits 114 defining tabs 116 which are bent inwardly to engage an inwardly tapered surface 15a of the socket 15. The tabs 116 are bent outwardly to form flanges as at 118. A clamp band 120, secured by a bolt 122, is wrapped around the tabs 116, resting at its lower edge against the flanges 118, thus securing the tabs 116 firmly to the blade socket and securing the manifold band 106 in position upon the blade socket.

The band 106 is provided at the rearward portion of the propeller, with an opening 124 embracing a ferrule 126 secured to and passing through an opening in the disc 34. This ferrule provides an entry for hot gases from the manifold 38 to the zone surrounding the blade shank, outboard of the hub socket. The blade shank is provided with a gas entrance opening 24 for passage of gas into the hollow interior of the propeller blade 16.

The propeller blade shank is equipped with a vented streamlined cuff 130, secured to the blade through a split forging 132 which embraces the blade shank, said split forging being anchored in position by bolts 134. Since the interior of the cuff 130 is hollow, and since the exterior of the cuff is subject to ice accretion in the same fashion as the blade is so subject, it is desirable in a cuffed propeller to make provisions for warming it. Accordingly, we provide a segmental duct 136 which extends from the chamber 138 formed by the band 106 outwardly through the forging 132 so that hot gas may flow from the blade chamber into the cuff hollow. This duct 136 is secured to an inner portion of the forging 132, the latter providing a partial closure for the outer end of the blade embracing chamber. The portion of the forging 132 which embraces and contacts the blade 16 is shown at 140, said portion having a groove fitted to an annular rib 142 formed on the blade shank 16. This rib constrains the cuff assembly from outward displacement due to the action of centrifugal force.

A clamp ring 144 embraces the forging portion 140 and carries a flat ring 146 forming the remainder of the outer closure for the chamber 138. Said flat ring forms a sealing abutment for a piston ring seal 150 which bears at its periphery on a wear surface 152 integral with the band 106, the outer side face of the ring seal 150 bearing upon the inner face of the flat ring 146 under the influence of centrifugal force. This provides a sealing closure for the chamber 138 and permits relative weaving between the propeller blade and its socket along with rotational freedom of the blade in its socket for pitch change. The major portion of the band assembly of which the band 106 forms a part of rigidly secured to the propeller hub, while the outer closure portion is

rigidly secured to the propeller blade shank. It will be noted that the duct 136 feeding hot gas to the cuff 130 is also rigidly secured to the propeller blade so that it may move therewith and with respect to the propeller hub.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

What is claimed is:

- 15 1. As an article of manufacture for use on a propeller including a socket and a blade rotatably secured therein said blade having a port outboard of the blade socket; a split ring for assembly around the blade shank and secured to the outer end of the socket, an open ended flexible band embracing said ring and embracing the blade shank in spaced relation including means to engage said ring and means to clamp the band tightly around the ring, said band including an opening for communication with a hot gas supply, another split ring secured adjacent the edge of and to said band at the edge thereof remote from said socket, and means for sealing the relatively rotatable blade shank and outer split ring to one 20 another, said rings, band and sealing means being mountable on said propeller with the blade installed in its socket.
- 25 2. As an article for use in a controllable pitch propeller including a rotatable hub having blade 20 sockets extending therefrom and having a blade mounted for pitch change in each socket, each blade having an aperture in its wall outboard of said socket; an annular band surrounding each blade, secured in sealed relation to the outer end 30 of its socket, and defining between the blade and band an annular chamber communicating with the blade aperture, a closure for the outer end of said annular chamber having a portion secured to the outer edge of the band and a portion sealingly engaging the blade shank, said portions having overlapping relation to provide a seal for said chamber and to allow of relative movement between said blade, band and band-secured closure portion, a conduit in said band through which 35 a hot fluid medium may be fed to said chamber and thence to said blade through the blade aperture, a hollow cuff embracing and secured to said blade outboard of said band, and a conduit secured to one of said chamber closure proportions and 40 entering into the hollow of said cuff.
- 45 5. As an article for use in a controllable pitch propeller including a rotatable hub having blade 40 sockets extending therefrom and having a blade mounted for pitch change in each socket, each blade having an aperture in its wall outboard of said socket; an annular band surrounding each blade, secured in sealed relation to the outer end 50 of its socket, and defining between the blade and band an annular chamber communicating with the blade aperture, a closure for the outer end of said annular chamber having a portion secured to the outer edge of the band and a portion sealingly engaging the blade shank, said portions having overlapping relation to provide a seal for said chamber and to allow of relative movement between said blade, band and band-secured closure portion, a conduit in said band through which 55 a hot fluid medium may be fed to said chamber and thence to said blade through the blade aperture, a hollow cuff embracing and secured to said blade outboard of said band, and a conduit secured to one of said chamber closure proportions and entering into the hollow of said cuff.

CHARLES W. CHILLSON.
